HANDBAG STRUCTURE

Preston Upham, Brookline, Mass., assignor to
 United-Carr Fastener Corporation, Cambridge,
 Mass., a corporation of Massachusetts

Application May 10, 1935, Serial No. 20,742

2 Claims. (Cl. 150—29)

My invention relates to improvements in handbags and the like containers, and, more particularly, to the hinging together of the members, and also to a novel and simple means of detachably securing an inner frame to an outer frame.

In the drawing, which represents a preferred embodiment of my invention:

Figure 1 is a top view of my improved handbag in closed position;

Fig. 2 is a front view of my handbag;

Fig. 3 is a top plan view of my handbag in open position;

Fig. 4 is an enlarged section taken on the line 4—4 of Fig. 1;

Fig. 5 is an enlarged section of my improved outer frame hinging device with my inner purse frame in assembly therewith;

Fig. 6 is an enlarged section of my improved outer frame hinging device with my inner purse frame detached from the outer frame;

Fig. 7 is a section taken on the line 7—7 of Fig. 6; and

Fig. 8 is an enlarged view of my improved outer frame hinging device.

Referring to the drawing, Figs. 1 and 2 show a handbag having the front and rear walls 1 and 2 and the end walls 3. In Fig. 5, I have illustrated a preferred frame structure of the U-shaped cross-section type where the material of the front and rear side walls 1 and 2 is brought over the outer walls 4 of the frame members and anchored between those walls and their inner walls 5.

Referring to my improved frame construction, at their points of connection, I have shown in Fig. 3 a pair of U-shaped outer frame members 9 and 10. Integral with the free end of one leg 11 of each member is an ear-shaped element 12 having an aperture 12a therein. Integral with the free end of the other leg 13 of each member is a hollow bearing 14. The elements 12 and 14 are pivotally held together at each end of the frame by a rivet such as a hollow pin 15, as shown in Figs. 5, 6 and 8.

The pin 15 runs the width of the bag frame and, in my preferred form, the hollow bearing 14 and the ear-shaped element 12 will together (as shown in Fig. 8) bear upon the entire surface of the pin 15. The element 12 is located on the pin between an end of the bearing 14 and a turned back end 15a of the pin 15. As a result of this position, one face of the element 12 will abut an end of the hollow bearing 14 and its opposite face will abut the turned back portion 15a of the rivet pin 15. The result of the con-

struction described above is that, due to the wide continuous surface of the bearing element 14 and the compact manner in which the free ends of the frame members have been assembled together at each end of the bag with the pivot pins, the parallel lateral movement of the frames prevalent in many bag frames is eliminated, and a particularly strong, yet simple, hinging device is provided.

Located within and attached to the outer frame 10 is a purse which is concealed within the handbag when the handbag is closed, but which is exposed to view and available for easy entrance when the handbag is open. The frame for the purse comprises the frame members 16 and 17 15 which are held in closed position by the cam means 18 (Fig. 3).

The frame members 16 and 17 are of a substantially channel shape in cross-section, the free ends of each member being provided with 20 the ear-shaped elements 19 which are connected at each end of the frame by the pivot pin 20, as shown in Figs. 5-7. The pin 20 comprises an attaching portion 21, a flange portion 22, and the pivot portion 23.

When the purse is assembled with the outer bag frames 9 and 10, an attaching portion 21 at one end of the purse frame is inserted into one of the hollow rivets 15; opposite adjacent ends of the frame members 16 and 17 are then pressed toward 30 the attached portion whereby the natural spring action in the frame members 16 and 17 will allow the attaching portion 21 at the other end of the purse frame to be inserted into its corresponding hollow rivet 15. After assembling the purse 35 frame with the outer frame, the spring qualities of the purse frame will prevent the easy disengagement of the attaching portions 21 from their seats, but the purse frame may be easily and quickly detached from the outer frame, if it is 40 purposely so desired, by reversing the assembling process described above.

The flanges 22 of the pin 20 will prevent the ear-shaped elements of the purse frame member ends from slipping over the attaching portions 21 before assembly with the outer frame, and the portions 23 will provide a suitable means upon which the corresponding frame end elements may pivot in order to carry out the opening and closing of the purse.

Each of the outer frame members illustrated have, as shown in Fig. 4, a flange means 6 extending inwardly from the outer wall thereby causing the bag material to project over the inner walls 5, which, in order to carry out my pur-

pose, have been made shorter than the outer walls 4. As a result of this construction, the frames will be completely hidden by the bag material and the bag will be given a very attractive 5 appearance.

As a means for fastening the bag frames together, I have provided the cams 7, as shown in Fig. 4, which are attached to the frame members in any suitable manner and so located within 10 in the handbag that they are concealed from view when the bag frames are in closed position. The knobs 8 (Figs. 1-3) are located on the walls 1 and 2 of the handbag and used, in my preferred form, for drawing the cams apart by a 15 lateral pull upon the same.

Although I have illustrated and described a preferred embodiment of my invention, I do not wish to be limited thereby, because the scope of my invention is best defined by the following 20 claims.

I claim:

1. A handbag frame having a pair of frame members of channel-shaped cross-section formed with bottom and side walls, a hinge construction 25 for each end of the frame, each hinge construction comprising a flat ear formed as an extension of the channel bottom of one frame member at the end thereof and constituting the sole

hinge element for that frame member, a hollow bearing formed as an extension of one of the side walls of the other frame member and constituting the sole hinge element for that frame member, and a hinge pin passing through said ear and bearing and securing them in pivotally assembled relation. 5

2. A handbag frame having a pair of frame members of channel-shaped cross-section formed with bottom and side walls, a hinge construction 10 for each end of the frame, each hinge construction comprising a flat ear formed as an extension of the channel bottom of one frame member at the end thereof and constituting the sole hinge element for that frame member, a hollow 15 bearing formed as an extension of one of the side walls of the other frame member and constituting the sole hinge element for that frame member, and a hinge pin passing through said ear and bearing and securing them in pivotally 20 assembled relation, said cooperating ear and bearing, when assembled, being confined within the planes of the marginal edges of said channels and having continuous bearing upon said hinge pin throughout the width of said channel mem- 25 bers.

PRESTON UPHAM.
